CLOSURE FOR BUNGHOLES

Victor Alvear, Clifton, N. J.

Application December 6, 1947, Serial No. 790,108

3 Claims. (CL 217—98)

1

My invention relates to devices to be used to close the filling bung holes especially of beer barrels or kegs which are subject not only to normal liquid and gas pressures but also to changes in temperature and to sudden shocks.

The object is to provide an effective closure of simple and inexpensive form which can be readily applied and readily removed.

Another object is to provide a closure which will be effective and reliable even when subjected to a wide range of temperature changes.

It is of the type of my former Patent 2,325,356 but is capable of withstanding much greater changes in pressure and is more effective and adaptable to irregularities in bung holes and in the dimension of the closure itself.

For this purpose, the closure has a cup-like sheet metal body having a flaring rim and closed at the bottom. This has a depressed central portion to which a non-metallic cup is attached. This cup has an elastic and compressible side wall embracing the side wall of the body but not attached to it. This closure is adapted to be driven into a tapered bung hole and frictionally wedged therein. When it is desired to remove the closure it is merely necessary to puncture the bottom of it and insert in the opening thus formed a tool for extracting the closure.

Fig. 1 is an edge view and partial section of the main steel cup-like closure member on an enlarged scale.

Fig. 2 is an edge view and partial section of the packing or gasket member used with the closure member of Fig. 1.

Fig. 3 is an edge view and partial section showing the two members of Figs. 1 and 2 assembled and ready for use.

Fig. 4 is a sectional view showing the closure of Fig. 3 installed in the bung hole of a barrel and showing in dotted lines the relation of the closure as it is being inserted into the bung hole.

Fig. 5 is a sectional view showing on a still larger scale a fragment of a closure.

The body 10 of the closure consists of a drawn steel cup having a tapered side wall 11 and a resilient bottom having a central depressed portion 12 surrounded by an annular platform 13 which connects the central portion with the side wall. The upper edge 14 is flared outwardly.

The covering, packing or gasket 15 has a side wall 16 and is formed to fit the center, bottom and side wall of the closure body. This covering is water and gas tight and somewhat elastic and is cemented in any suitable manner to the bottom of the depressed center 12 of the closure body 55

and is preferably free from or unattached to the platform 13 and side wall 11.

The barrel has a circular bung hole 17 in a metal portion 18, the wall 19 of which is conically tapered slightly inwardly at a small angle for instance tapering from 1½ inches at the entrance to 1¾ inches at the inside, the wall being a little more than 1 inch thick.

The side walls of the closure body and of the packing are inclined at substantially the same angle as the taper of the wall 19 of the bung hole and the diameters are such that the closure will seat at the approximate center of the side wall of the bung hole, the flange 14 touching the wall 19 and the wall of the packing 15 being compressed between the walls 11 and 16.

The closure body 10 is formed preferably of sheet steel about .014 inch thick and at its bottom is resilient, being offset or depressed about .010 inch so that when the closure is forced into the bung hole the bottom is sprung downwardly and its outer diameter contracted slightly. When the pressure on the closure is released, the bottom springs back and increases the compression of the side wall 16 of the packing, the action being somewhat like a toggle.

The friction due to forcing the closure into the bung hole draws the side wall 16 of the packing upwardly so that the material is stretched from the position of Fig. 3 to that of Fig. 4. This stretching action is made possible by reason of the elasticity of the material and the fact that it is not secured to the bottom of the platform 13 nor to the side wall 11.

To facilitate this compression and stretching, I prefer to form the packing piece from a composite material having a layer 20 of compressible pulp board covered with a layer 21 of paper and an outer film 22 of elastic rubber-like material which is water and gas tight and unaffected by the substance contained in the barrel. This packing may conveniently be .025 inch thick.

It will be understood that the packing 15 and the body 10 of the closure may be formed separately or connected together and drawn into cup-shape in one or more operations.

The flange 14 grips the side wall of the bung hole tightly and the packing material seals the closure both from within and from without.

When the closure is in place, it has been found that it will withstand much greater pressure than a barrel is subjected to even in hot weather and even when a barrel is dropped or struck with a mallet.

This strange resistance to outward stress is

due to the fact that the bottom of the closure is distorted inwardly when inserted and is distorted or buckled outwardly under outward pressure.

The outer wall of the body of the closure may be decorated or marked with a name or trademark in any well known manner.

To remove the closure, the bottom is punctured with a suitable tool (not shown) which is inserted through the opening thus formed. The gas pressure being relieved, it is quite easy to withdraw the closure.

I claim:

1. A bung hole closure comprising a drawn steel cup body having an inclined side wall flared outwardly at its rim and having a closed central depressed portion surrounded by an annular portion and an elastic packing cup cemented to the depressed central portion of the body but free from said annular portion and having a side wall free to be drawn around the side wall of the body when the closure is driven into a bung hole.

2. A bung hole closure comprising a steel cup closed at the bottom and having a tapered side wall terminating in an outwardly extending flange and a non-metallic cup-like covering formed of a composite fabric having a com-

pressible inner layer and an elastic water and gas-proof outer film, the inner layer of the fabric being cemented to the central portion of the bottom of the steel cup and its side wall embracing the outer wall of the steel cup but left unattached and free to be drawn along the wall of the cup when the closure is forced into a bung hole having a tapered side wall.

3. A closure as set forth in claim 1 in which the elastic packing cup is formed of a composite material having a layer of compressible pulp board covered with paper and an outer film of elastic, rubber-like material which is water and gas tight.
